(57) **CLAIM**

The ornamental design for a handling apparatus, as shown and described.

DESCRIPTION

FIG. 1 is an isometric view of a front side and a right side of one embodiment of a handling apparatus;

FIG. 2 is an isometric view of the front side and a left side of the handling apparatus of FIG. 1;

FIG. 3 is an isometric view of a rear side and the right side of the handling apparatus of FIG. 1;

FIG. 4 is an isometric view of the rear side and the left side of the handling apparatus of FIG. 1;

FIG. 5 is a right side elevational view of the handling apparatus of FIG. 1;

FIG. 6 is a left side elevational view of the handling apparatus of FIG. 1;

FIG. 7 is a front elevational view of the handling apparatus of FIG. 1;

FIG. 8 is a rear elevational view of the handling apparatus of FIG. 1;

FIG. 9 is a top plan view of the handling apparatus of FIG. 1;

FIG. 10 is an isometric view of a front side and a right side of another embodiment of a handling apparatus;

FIG. 11 is an isometric view of the front side and a left side of the handling apparatus of FIG. 10;

FIG. 12 is an isometric view of a rear side and the right side of the handling apparatus of FIG. 10;

FIG. 13 is an isometric view of the rear side and the left side of the handling apparatus of FIG. 10;

FIG. 14 is a right side elevational view of the handling apparatus of FIG. 10;

FIG. 15 is a left side elevational view of the handling apparatus of FIG. 10;

FIG. 16 is a front elevational view of the handling apparatus of FIG. 10;

FIG. 17 is a rear elevational view of the handling apparatus of FIG. 10; and,

FIG. 18 is a top plan view of the handling apparatus of FIG. 10.

The broken lines are for the purpose of illustrating environmental structure and form no part of the claimed design.

1 Claim, 18 Drawing Sheets
